NON-REFILLABLE BOTTLES

George K. Laham, Roslindale, Mass.

Application May 7, 1954, Serial No. 428,350

2 Claims. (Cl. 215—28)

This invention relates to improvements in non-refillable bottles and more particularly to a simplified structure for such bottles which is inexpensive to produce and effective for preventing any appreciable inflow of liquid into the bottle during attempts to refill the bottle or to adulterate the remaining contents of a bottle from which some of the original contents may have been poured.

It is among the objects of the invention to provide a non-refillable bottle wherein a permanently secured cap member has two non-straight passages therethrough respectively for out-flow of liquid and inflow of air, the said passages coacting with a valve element to permit free outflow of liquid when the bottle is tilted to an outflow inclination but having extent and arrangement making it extremely difficult if not impossible to insert a wire or other element, through either of the passages into a position to lift or hold the valve element from its seat during any attempt to flow liquid into the bottle.

Another object of the invention is to provide a non-refillable bottle wherein a valve element normally seats by gravity to close the bottle and wherein generally diametrically opposite passages serve for outflow of liquid and inflow of air respectively, each said passage having an abrupt change of direction which makes it difficult to insert any element through the passage into engagement with the valve element.

It is, moreover, my purpose and object generally to improve the structure and effectiveness of non-refillable bottles, and more especially to accomplish the mentioned objectives simply and economically.

In the accompanying drawing:

Fig. 1 is a medial cross-sectional view of the upper portion of a non-refillable bottle embodying features of the invention;

Fig. 2 is a similar view of the bottle of Fig. 1 in condition for dispensing liquid contents of the bottle;

Fig. 3 is a perspective view of the valve element which is shown in the neck of the bottle in Figs. 1 and 2; and

Fig. 4 is a fragmentary cross-sectional view showing a modified form of out-flow passage.

Referring to the drawing, the neck portion 10 of a bottle is exteriorly threaded at 12 around the mouth end of the neck. A cap member 14, of plastic or any other suitable material, has one end relatively deeply chambered at 16 with the walls of the chamber interiorly threaded at 18 for screwing on the threaded portion of the neck 10. However, before the cap is screwed on neck 10, a substantial coating of cement 20, or the like, is applied to the threads 12 and/or the threads 18 to effect a permanent securing of the cap on the bottle neck when the cap is screwed tight on the neck and the cement 20 is allowed to set.

According to the invention, a tapering valve element 22 engages loosely in the mouth opening 24 of the bottle and has an annular flange 26 at its larger diameter end for resting upon or engaging against the mouth end of the bottle when the bottle is in upright position, or when pressure of liquid may force the valve element to seated

condition even though the bottle may be in any tilted position, or bottom end up, assuming an effort to force liquid into the bottle. The valve element has a pin 28, or the like, projecting axially from its flanged end for maintaining the flanged end of the valve element substantially spaced from the end wall 17 of the chamber 16 when the valve element is unseated enough to cause pin 28 to engage the end wall 17 of chamber 16.

Preferably, a small-diameter passage 30 extends through the valve element 22, from one end to the other, for a purpose which later will appear.

The cap member 14 has an outflow passage 32 leading from the chamber 16 through solid portions of the cap member and opening through an end portion of the cap 15 which may be provided with a relatively short pouring spout 34 whose outlet is shown closed by the removable closure 36.

Another passage 38 leads from chamber 16 through solid portions of cap member 14 and opens through an 20 end portion of the cap member, preferably at a diametrically opposite location in the cap member from the outflow passage 32.

It is a feature of the invention that each of the two 25 passages 32, 38 has an abrupt change of direction within solid portions of the cap member with the portion of each which is adjacent to the location of its opening into chamber 16 extending obliquely outward to a location which preferably is closely adjacent to the juncture of the side and bottom walls of the chamber. As illustrated in 30 the drawing the outflow passage 32 has a straight part 32^a extending a substantial distance inwardly and downwardly from the spout 34 and has a generally right-angular related straight part 32^b extending downwardly and outwardly from the inner end of part 32^a and opening into 35 chamber 16 close to the said juncture of the chamber's side and end walls. Hence, in any effort to insert a wire or other element through the outflow passage for lifting or holding the valve element 22 from its seat, the inserted element must negotiate a right-angle bend and, if successful in doing that, its inner end will be directed against the top end of bottle neck 10 with substantially no possibility that it can become engaged between the valve element and its seat.

Passage 38 in cap member 14 is generally similar to 45 outflow passage 32 but of much smaller diameter. It has generally right angularly related parts 38^a, 38^b, with the part 38^b opening into chamber 16 close to the juncture of the chamber's side and end walls at a location which may be diametrically opposite the location of the 50 opening of part 32^b into chamber 16. This passage 38 is a vent passage whose outer end may be closed by a strip of tape 40, or the like, after filling of the bottle and the passage ordinarily will continue closed during storage and shipment, the tape being removed when the 55 bottle initially is to dispense contents, after which the vent passage may be left open, assuming that contents of the bottle will be completely dispensed within a reasonable length of time. However, if contents are to stand indefinitely in the bottle after the initial dispensing of 60 contents, the vent passage preferably will be again covered with tape or the like.

It will be apparent that any attempt to lift or hold 65 valve element 22 from its seat by a wire or other element inserted in passage 38 will meet with even greater difficulty than in the similar attempt through passage 32.

When pouring from the illustrated bottle, the tape 40 and closure 36 will be removed and the bottle tilted to the position generally illustrated in Fig. 2, with the spout 34 directed downward. In this tilted position of the bottle, valve element 22 will be unseated but the projecting pin 28 on the valve element maintains it in

spaced relation to the end wall 17 of chamber 16, so that liquid from the bottle can flow relatively freely around the valve element and through the outflow passage 32. The inner end of vent passage 38 meanwhile is elevated to an extent which ordinarily permits inflow of air to replace the out-flowing liquid thus facilitating rapid and continuous out-pouring of liquid. If the liquid should rise above the inner end of the vent passage, a slight issuing of liquid from the vent provides a signal to the pourer to place a finger over the outer end of the vent until the tilt of the bottle is reduced enough to again uncover the inner end of the vent passage 38.

The minute passage 30 through the valve element 22 facilitates unseating of the valve element by equalizing the pressure at opposite sides of the valve element.

It may be desirable in some cases to further increase the difficulty of inserting a wire, or the like, through the outflow passage in cap member 14. This may be accomplished by providing staggered projections along the outflow passage, or along either part 32^a or 32^b thereof, as illustrated at 42 in Fig. 4.

While I have disclosed what I now consider to be a preferred embodiment of the invention, various changes may be made in structural details within the scope of the appended claims, and it is intended that the patent shall cover, by suitable expression in the appended claims, whatever features of patentable novelty exist in the invention disclosed.

I claim as my invention:

1. A non-refillable bottle having an outflow opening at one end, a valve element having a tapering body for extending loosely into said outflow opening and having the larger diameter end portion of said tapering body adapted to engage the walls of said outflow opening for guiding said valve element and closing said opening and having an annular flange at the large diameter end of said body for seating against the end of the bottle around said outflow opening when said tapering body is entirely within said opening, a cap arranged over said outflow opening and the said valve element therein and permanently secured to the open end portion of the bottle exteriorly thereof, said cap having wall portions defining a substantial interior chamber opposite said valve ele-

5

ment into which chamber said valve element can move outwardly with simultaneous withdrawal of the valve element from said outflow opening, a projection on the flanged end of said valve element arranged for coaction with that wall of said chamber which is opposite said outflow opening thereby to stop said outward movement of the valve element short of said chamber wall, means defining a single minute relatively long vent passage extending entirely through said valve element from one end to the other thereof, said vent passage equalizing gaseous pressure within the bottle and in said cap chamber when the valve element is seated and being adapted to be closed by liquid against passage therethrough of either liquid or gas, an outflow passage extending from said cap chamber and opening through the cap at an outer end portion thereof, and a vent passage extending from said cap chamber and opening through the cap at an outer end portion thereof, each of said outflow passage and vent passage having an abrupt change of course within said cap and said passages opening through the cap at generally opposite sides thereof.

2. A non-refillable bottle as defined in claim 1 wherein the inner ends of said outflow and vent passages in said cap open out of said cap chamber closely adjacent to the periphery of the chamber at opposite sides of the chamber.
